US00D916400S

(12) **United States Design Patent** (10) Patent No.: **US D916,400 S**
(45) Date of Patent: **** Apr. 13, 2021**

(54) **ULTRASONIC CLEANER**

(71) Applicant: **Elma Schmidbauer GmbH**, Singen (DE)

(72) Inventor: **Raphael Eckstein**, Singen (DE)

(73) Assignee: **Elma Schmidbauer GmbH**, Singen (DE)

(**) Term: **15 Years**

(21) Appl. No.: **35/505,145**

(22) Filed: **Apr. 23, 2018**

(80) **Hague Agreement Data**

Int. Filing Date: **Apr. 23, 2018**

Int. Reg. No.: **DM/101507**

Int. Reg. Date: **Apr. 23, 2018**

Int. Reg. Pub. Date: **Jun. 22, 2018**

(51) LOC (13) Cl. **15-05**

(52) U.S. Cl.

USPC **D32/1**

(58) **Field of Classification Search**
